UNITED STATES PATENT OFFICE.

PETER D. HOE, OF HONOLULU, TERRITORY OF HAWAII.

WHEELBARROW.

1,261,532.

Specification of Letters Patent.

Patented Apr. 2, 1918.

Application filed December 19, 1916. Serial No. 137,886.

To all whom it may concern:

Be it known that I, PETER D. HOE, a citizen of the United States, residing at Honolulu, in the Territory of Hawaii, have invented new and useful Improvements in Wheelbarrows, of which the following is a specification.

This invention relates to wheel barrows.

The object of the invention is to provide 10 a wheel barrow whereby the load may be dumped in front of the same, for convenient use in restricted spaces.

A further object of the invention is to provide a wheel barrow with a forwardly 15 tilting body, capable of dumping its load in front, with means for automatically returning the said body to its original position.

A still further object is the provision of 20 a wheel barrow of this class, with means for absorbing the shock of the body as it is returned to its normal position.

A still further object of the invention is to construct a wheel barrow in a simple, durable and efficient manner, which is capable 25 of use in restricted spaces.

In the drawings:—

Figure 1 is a side elevation of a wheel barrow constructed in accordance with the present invention showing the body in its 30 normal position upon the side bars;

Fig. 2 is a similar view with the body in position for dumping;

Fig. 3 is a rear elevation of the same showing the body in the position of Fig. 1;

Fig. 4 is a front view;

Fig. 5 is a detailed view illustrating the plunger about within the socket of the handle bar, the said socket being shown in section;

Fig. 6 is a detailed longitudinal section through one of the handle bars illustrating the pulley mounted thereon; and

Fig. 7 is a detailed longitudinal section through the housing containing the spring actuated drum for the cable.

For various reasons it is often inconvenient to dump a load from a wheel barrow from the side, and for this reason I have devised the following described barrow, which 50 is capable of both side and forward dumping.

Referring in detail to the drawings the improved barrow as illustrated consists of the usual side bars 1 forming a mounting 55 for the wheel 2, and the handles 3. The wheel is mounted upon the underside of the

side bars by means of suitable bearings 4, the said side bars converging at this end in the ordinary manner.

Mounted upon the side bars is a body 5, 60 in the present instance shown as a one piece metal body, but it is obvious that a body of any desired construction may be substituted. This body is not rigidly secured to the side bars, but is held thereon by means of hinges 65 having one leaf 6 bolted to the bars 1 by means of bolts 8, which pass through the said bars and engage the bearings 4 to hold them in position.

The other leaf 7 of the hinge has its end 70 bent at an obtuse angle, and is riveted or otherwise secured to the forward inclined end of the body 5. The length of the leaf 7 is such that when the body is tilted upwardly and forwardly it will permit the 75 said body to clear the wheel until it has reached a sufficient height to dump the load. Secured to the side bars at a point about centrally of their length, are guiding and limiting hinges 9. These hinges are of a 80 triple type, that is, they are provided with three pivot points and four leaves. One of these leaves is secured to the side bars as at 10, and another of the leaves is secured to the underside of the body as shown at 11, 85 while the pivotal points 12 and 13 permit the leaves 14 and 15 to be folded upon themselves in a compact manner. It will thus be seen that the hinges 9 act as a guide to steady the body as it is being raised and 90 lowered, and to limit the movement of the body in its raised position.

Means are provided for automatically returning the body to its normal position as soon as the load has been dumped, this 95 means consisting of cables 16 secured to the rear of the body as at 17, and passing over pulleys 18, mounted within sockets 19 mortised in the side bars. The opposite ends of these cables are adapted to be wound 100 upon a spring actuated drum or pulley 20 mounted within housings 21 secured to the underside of the side bars.

Shock absorbing elements are provided in connection with the automatic returning 105 means, the said shock absorbing element consisting of preferably metal sockets 22 countersunk in the side bars, and plungers 23 secured to the underside of the body 5 in such position as to enter the sockets as 110 the body is set upon the said side bars. In order to permit the plungers 23 to more

readily enter the sockets 22, they are tapered upon their lower ends, but their upper ends are of a diameter to snugly fit the sockets 22 in order to provide an air cushion 5 to absorb the shock.

A hook 24 secured to the rear of the body 5 is adapted to engage the headed stud 25 carried by a cross bar 26 located between the side bars 1.

10 As a means for strengthening the bars 1 they are further provided with a cross bar 27 secured between the legs 28 and connecting bars 29. An additional cross bar 30 is located between the bars 1 at a point in the 15 rear of the wheel 2.

When it is desired to dump the barrow, the body is tilted upwardly and forwardly, until it assumes the position shown in Fig. 2, the guiding and limiting hinged rods serving to limit the forward movement of the body and hold it in proper position until emptied. The joint of this rod is then broken, when the spring controlled cables 16 will return the body to its normal position, the jar incident to the return of the body being taken up by an air cushion provided by the plungers 23 entering the sockets 22.

From the foregoing description when taken in connection with the accompanying drawings, it will be seen that the invention provides a wheel barrow capable of both forward and side dumping, the hook 24 permitting the body to be rigidly secured to the side bars when the barrow is dumped from the side.

Various changes in the form and proportion of the invention may be made as will properly fall within the scope of the claims 40 hereto appended.

Having described the invention, what I claim, is;

1. A wheel barrow comprising a frame, a

wheel mounted therein, a body having one end hinged to said frame in a manner to permit of the opposite end being raised to assume a dumping position and means including a spring actuated drum for returning the body to its normal position. 45

2. A wheel barrow comprising a frame including side bars, a wheel mounted between said bars, a body having one end hinged to said frame in a manner to permit of the opposite end being raised to assume a dumping position, a cable connected to said body, 50 rollers mounted upon the side bars for guiding said cable and a spring actuated drum secured to said frame beneath the body for automatically returning the body to its normal position. 60

3. A wheel barrow comprising a frame, a wheel mounted therein, a body hinged to said frame and capable of a swinging movement independent thereof and an air cushion provided between said body and frame 65 for absorbing the jar of the body when swung into position upon the frame.

4. A wheel barrow comprising a frame, a wheel mounted therein, a body hinged to said frame and capable of swinging movement independent thereof and means including plungers carried by the body and engageable with sockets carried by the frame for absorbing the jar of the body when swung into position upon the frame. 70 75

5. A wheel barrow comprising a frame, a wheel mounted therein, a body hinged to said frame and capable of a swinging movement independent thereof and means including jointed rods, each having one end hingeably connected to the body and the other end hingeably connected to the frame for limiting the swinging movement of the body. 80

In testimony whereof I affix my signature,

PETER D. HOE.
